UNITED STATES PATENT OFFICE.

MARTIN GILLESPIE, OF SMITH'S FERRY, PENNSYLVANIA.

IMPROVEMENT IN REAMERS FOR ENLARGING OIL-WELLS.

Specification forming part of Letters Patent No. **141,344**, dated July 29, 1873; application filed June 17, 1873.

To all whom it may concern:

Be it known that I, MARTIN GILLESPIE, of Smith's Ferry, in the county of Beaver and State of Pennsylvania, have invented a new and Improved Reamer for Enlarging Oil-Wells; and I do hereby declare the following to be a full, clear, and exact description of the same, reference being had to the accompanying drawing forming part of this specification, in which—

The drawing is a vertical sectional elevation, exhibiting all the features of my invention.

The invention relates to a novel method of enlarging the bore of an oil or analogous well, and in peculiar means for carrying out this method, as hereinafter fully described and subsequently pointed out in the claims.

In the drawing, B represents an oil-well whose bore it is desired to enlarge at any portion thereof. B is a reaming-tool, having the cutter b and the inwardly-inclined centering-pin b', that works in a bearing, c, of the tube C. This tube is inwardly beveled at the upper and lower end, and may be recessed in the middle, so as to leave at each end only an an-

nular flange that comes in immediate and frictional contact with the side of well.

I fill the well with sand up to the highest point where the enlargement is to commence, and then drop down thereinto the tubular bearing C. The tool is then let down, the journal b entering the tube C, and being thereby centered and guided in its rotary motion. The sand supports the centering-tube C, but, as the tool presses upon the latter, works up through the tube. The cavity of this tube is preferably enlarged from the top toward the bottom, so as to increase its capacity and facilitate the upward movement of the sand.

Having thus described my invention, what I claim as new, and desire to secure by Letters Patent, is—

1. A reaming-tool having the cutter b and pin b', combined with a centering device that receives said pin.
2. A centering device, C, for a reamer, made tubular.

MARTIN GILLESPIE.
